UNITED STATES PATENT OFFICE.

ROBERT C. RUSSELL, OF PITTSBURGH, PENNSYLVANIA

CARD INDEX.

Application filed November 14, 1922. Serial No. 600,927.

To all whom it may concern:

Be it known that I, ROBERT C. RUSSELL, a citizen of the United States, and a resident of Pittsburgh, in the county of Allegheny and State of Pennsylvania, have invented certain new and useful Improvements in Card Indexes; and I do hereby declare the following to be a full, clear, and exact description of the invention, such as will enable others skilled in the art to which it appertains to make and use the same.

This invention relates to improvements in card indexes of the visible type, in which the cards are mounted in a holder or slide and overlie each other.

The objects of my present invention are to so construct the cards and means whereby they are mounted in the holder or slide that said cards will lie flatly when in normal position or when reversed; to permit easy manipulation of the cards; to enable the cards to be readily moved either singly or collectively in the holder or slide; to so hinge the cards to their supports that the latter shall have an interlocking relation, preventing removal of more than one card at a time from the holder but permitting the support of one card to be unlocked from the support of the adjacent card and then readily removed with its card from the holder, and to so construct the support for each card that a card with its support may be easily and quickly inserted in proper place in the holder or removed from the latter.

With these and other objects in view, the invention consists in certain novel features of construction and combinations of parts as hereinafter set forth and pointed out in the claims.

In the accompanying drawings,—

Figure 1 is a face view of a card index embodying my improvements;

Figure 1^a is a longitudinal sectional view of the same.

Figure 2 is a front perspective view of one of the cards and its support;

Figure 3 is a rear perspective view of one of the cards and its support;

Figure 4 is an enlarged view in perspective and partly in section showing a card and support and the slot in the hinging material for the passage of a tongue on the support of another card of the series;

Figure 5 is a transverse sectional view on the line 5—5 of Figure 1 illustrating the assembly of a plurality of card supports and attached cards, and

Figure 6 is a sectional view of a modification.

The holder 1 for the cards may be made of metal having inwardly turned side flanges 2, forming guide-ways for parts projecting from the card supports as more fully hereinafter explained. One end of the metal sheet forming said holder is bent to overlie the lower portion of the holder and provides a platform 3 upon which the bottom card of the series may rest and permit this card and the overlying cards to be disposed flatly. The lower portions of the side flanges 2 of the holder may be bent downwardly close against the platform 3 as at 4 and thus close the lower ends of the guide-ways formed by the major portions of said flanges and the upper end of the platform 3 may constitute an abutment for the support of the bottom card.

In the drawing (Figure 1) I have shown a plurality of cards 5 in the holder 1 and to the upper edge portion of each card 5, a strip of fabric 6 is cemented or otherwise secured. This fabric strip 6 is also cemented or otherwise secured to a card support 7 (preferably of card-board) in such manner as to provide a hinge for the card to said support. The fabric strip is secured to approximately one-half of the front face of the card support 7 so that the hinge-connection of the card to the support will be located approximately along the longitudinal center of the latter, and the fabric strip may be made to cover the entire back of the card support 7 if desired, or only sufficient fabric for attachment of the card and support to form a hinge, but when the fabric covers the entire back of the support and both sides of the tongues 8, it will serve to reinforce these parts. Each card support is made of a length somewhat greater than the horizontal width of a card so that laterally projecting tongues 8 will be provided to enter the guideways formed by the side flanges 2 of the slide or holder 1 and said tongues may be covered on both faces by the fabric 6. Each card support 7 is provided centrally between its ends with an upwardly projecting tongue 9, and the fabric strip 6 whereby the card 5

is hinged to its support 7 is provided centrally with a slot 10 to receive the tongue 9 of the support 7 of an adjacent card.

From the construction and arrangement of parts above described, it will be seen that the cards may be easily moved in the holder, being guided by the laterally projecting tongues 8 in the guide-ways of the holder, and that when the cards are assembled, there will be an interlocking relation effected between the card supports so that the cards cannot be withdrawn or removed collectively from the holder and hence the cards are in effect normally locked in the holder.

15 By moving a card and its holder away from an adjacent card, it can be moved from the holder in a direction forwardly at right angles to the latter and as this is done the lateral tongues 8 will move out of the guide-ways because the support 7 is sufficiently flexible to permit such bending as will cause the disengagement of the lateral tongues 8 from the guide-ways. Should it be desired to remove an intermediate card 20 or to insert a card in an intermediate position among the series of cards, the user may grasp the several cards above such intermediate position or even the lowermost cards above such intermediate position and slide 25 all of the upper cards collectively while in interlocked relation with each other, in an upward direction. To move such upper cards downwardly, the user may grasp the upper card only and pull it downwardly, 30 causing the downward movement of all of 35 the group of cards which had previously been moved upwardly.

The flexible hinges afforded by the fabric strips 6 between the cards and their supports 40 will permit the cards to lie flatly one upon another when in normal positions and also to lie flatly when in reversed or raised positions.

In the modified construction shown in 45 Figure 6, the fabric hinge material is omitted, and the card 5^a is provided with an integral flange 11 adapted to fold so as to be capable of overlying the upper portion of the card and provide a hinge member to 50 which the card support 7^a is secured by cementing or in any other desired manner. With this construction the slot (10^a) for the passage of an adjacent card may be 55 made in the upper edge portion of the card in close proximity to the hinge connection of the flange 11 therewith.

My improvements are simple in construc-

tion, permit the ready manipulation of the cards and allow the removal or insertion of cards singly.

Having fully described my invention what I claim as new and desire to secure by Letters Patent, is:—

1. A card index comprising a plurality of cards, and supports having hinge connection with said cards and provided with upwardly projecting tongues, the structure having slots adjacent to the hinge connection between the cards and supports for the passage of tongues of adjacent card supports. 65 70

2. In a card index, a combined card and card support having hinge connection with each other and having a slot adjacent to the hinge connection of the card to the support, said card support having laterally projecting tongues and also having a tongue projecting from its upper edge. 75

3. In a card index, a combined card and card support having hinge connection with each other and having a slot adjacent to the hinge connection of the card to the support, said card support having laterally projecting tongues and also having a tongue projecting from its upper edge, said card support being made of material capable of being flexed to cause the lateral tongues to move in directions toward each other. 80 85

4. A card index comprising a holder having parallel guide-ways, a plurality of cards, a support for each card spaced from the upper edge of the latter, a fabric strip connecting each support with its card and providing a hinge for the latter, each fabric strip having a slot between the support and card and each support having a tongue to enter the slot of the strip connecting an adjacent card and support, and lateral tongues projecting from each support and entering the guide-ways of the holder. 90 95 100

5. In a card index, a card, a flexible support therefor having an intermediate tongue and provided with laterally projecting tongues, and a fabric connecting said support and card and affording a hinge for the latter, said fabric strip having a slot located between the card and its support. 105

In testimony whereof, I have signed this specification in the presence of two subscribing witnesses.

ROBERT C. RUSSELL.
